UNITED STATES PATENT OFFICE.

HARRY J. ALVIS, OF EAST ST. LOUIS, ILLINOIS.

COMBUSTION-ENGINE.

1,189,187.

Specification of Letters Patent. Patented June 27, 1916.

Application filed January 11, 1913. Serial No. 741,464.

To all whom it may concern:

Be it known that I, HARRY J. ALVIS, a citizen of the United States, residing at East St. Louis, in the county of St. Clair and State of Illinois, have invented a certain new and useful Improvement in Combustion-Engines, of which the following is a specification.

My invention relates to improvements in internal combustion engines and is illustrated diagrammatically in one form in the accompanying drawings, wherein—

Figure 1 is a side elevation partly in section along line 1—1 of Figs. 2, 3 and 4; Fig. 2, a section along the line 2—2 of Figs. 1 and 3; Fig. 3 is an end elevation in part section; Fig. 4, a sectional view along the line 4—4 of Figs. 1 and 3; Fig. 5, a plan view of the sleeve valve; Fig. 6, an elevation partly in section along the line 6—6 of Fig. 5; Fig. 7 is a detail sectional view through one of the cylinders; Fig. 8 is a section along the line 8—8 of Figs. 2 and 4.

Like parts are indicated by like letters throughout the several figures.

A is a cylinder wall, A¹ the crank case, A² a valve gear housing. This housing is in the present instance cast integral with the cylinder wall in part and in part with the 30 crank case but it is quite evident that it may be made separately if so desired and bolted or riveted in place as the case may be.

B is a crank shaft provided with connecting rods B¹ and pistons B². The carbureter 35 C discharges into a Y-shaped manifold C¹ which in turn communicates with intake headers or manifolds C² C³.

C⁴ C⁵ are exhaust headers or manifolds which discharge through a common exhaust 40 pipe C⁶.

The cylinder A is of greater inside diameter than the piston B² and contains a sleeve S which functions as a sleeve valve and is provided about its lower edge with the spiral gear S¹ in mesh with a worm S² on the shaft S³ which shaft is driven from the crank shaft B by a silent chain S⁶ passing over the gear S⁴ on the shaft S³ and the gear S⁵ on the crank shaft B. The sleeve 50 S projects upwardly above the upward limit of the piston travel and forms the wall of the combustion chamber since it terminates only at the top of the cylinder. The upper portion of this sleeve is provided with ports S⁷ S⁸. The passages P¹ P² P³ P⁴ lead from the combustion chamber through the cylinder

der wall to the intake manifolds C² C³ respectively. The passages P¹ P³ and P² P⁴ are arranged diametrically opposed with respect to the cylinder. The passages P⁵ P⁶ 60 P⁷ P⁸ lead from the exhaust manifolds C⁴ C⁵ respectively to the combustion chamber and are also diametrically opposed in pairs with respect to the cylinder.

It will be evident that while I have shown 65 in my drawings an operative device, still many changes might be made both in size, shape and arrangement of parts without departing materially from the spirit of my invention and I wish therefore that my drawings be regarded as in a sense diagrammatic.

The passages Q Q¹ have at their lower extremities the exhaust ports Q² Q³ controlled by the sleeve S and adapted to be opened when the slots Q⁴ Q⁵ in the sleeve 70 are in line with the ports. The passages Q Q¹ communicate with the exhaust manifolds C⁴ C⁵ respectively.

The use and operation of my invention are as follows:—Assuming the piston as 80 shown in the cylinder on the right hand side of Fig. 1 to be at the lower extremity of its travel, the valve sleeve as it rotates in the direction indicated by the arrow will commence to open the exhaust ports and, as 85 the shaft continues its rotation, the ports will continue to open and the piston move upwardly in the cylinder expelling the burnt gases. As the piston approaches the end of its stroke the sleeve will have rotated to 90 such a point as to commence to close the exhaust ports and open the intake ports and as the piston commences its downward or suction stroke it will draw a charge of combustible gas from the carbureter through the 95 intake manifolds and intake ports into the cylinder the ports being meanwhile wide open. However, as the piston again commences its upward or compression stroke the ports will be closed by the forward rotation 100 of the sleeve and the piston will complete its upward movement for the compression stroke. The charge will be fired in any suitable and usual manner. The piston will again continue on its working stroke 105 returning to the relative position shown in Fig. 1 upon the right hand side with the exception that the sleeve will have made only a single one-half revolution and the port in the sleeve that was on the right hand 110 side of the engine will now be found on the left side of the engine and vice versa.

It will be evident that a different number of ports might be used by varying the relative speed of the sleeve and the engine although I have found that the arrangement herein shown has proved very satisfactory.

I claim:—

An internal combustion engine comprising a cylinder, a sleeve mounted for rotation therein, a piston mounted for reciprocation within the sleeve, a crank-shaft, a driving connection between it and the piston, means responsive to the rotation of the crank-shaft for rotating the sleeve, a pair 10 of intake and exhaust pipes arranged, one of each pair on diametrically opposed sides of the cylinders, the upper end of the sleeve being ported, intake and exhaust passages

within the cylinder walls diametrically opposed and communicating respectively with 20 the adjacent intake and exhaust pipes, the passage being controlled by the ported sleeve and being so arranged that as the ported sleeve rotates, it opens first the intake and then the exhaust passages, the ports in 25 the cylinder being adapted to operate first as intake and then as exhaust ports, and being arranged separate one from the other by substantially an angle of 180°.

In testimony whereof, I affix my signature 30 in the presence of two witnesses this 23rd day of December 1912.

HARRY J. ALVIS.
